VANITY CASE AND OTHER CONTAINERS

Jacques Kreisler, New Rochelle, N. Y., assignor to
 Jacques Kreisler Manufacturing Corporation,
 New York, N. Y.

Application March 23, 1937, Serial No. 132,567

4 Claims. (Cl. 220—29)

This invention relates to containers and more particularly to sheet metal containers intended primarily for use as vanity cases or compacts, although the invention may be applied to other containers as, for example, cigarette cases, purses, etc.

One object of the invention is to provide a container of novel and ornamental appearance.

Another object of the invention is the provision of a container of the class described with improved closure means designed to be securely held in closed position and readily and conveniently opened.

A further object of the invention is to provide a container of the class described simulating the appearance of an envelope and further to provide means for releasably securing the envelope-flap simulating part of the container in closed position.

A yet further object is generally to provide a vanity case of pleasing appearance and of simple and economical construction.

For accomplishing the above objects of the invention a container has been constructed as herein shown and described, and for a complete understanding of the invention reference is to be had to the following description considered with reference to the accompanying drawings.

In the drawings:

Fig. 1 is a perspective view of a vanity case embodying the present invention;

Fig. 2 is a perspective view of the vanity case showing the cover in partially open position.

Fig. 3 is a perspective view of the case showing the cover in fully open position;

Fig. 4 is a perspective view of the body portion of the container and part of the cover, with parts removed;

Fig. 5 is a perspective view of the powder tray and rouge compartment frame removed from the container;

Fig. 6 is a detail sectional view on the line 6—6 of Fig. 1;

Fig. 6a is a sectional view on the line 6a—6a of Fig. 2;

Fig. 7 is a sectional view on the line 7—7 of Fig. 4;

Fig. 8 is a sectional view on the line 8—8 of Fig. 3;

Fig. 9 is a detail sectional view on the line 9—9 of Fig. 8;

Fig. 10 is a sectional view on the line 10—10 of Fig. 1 showing a modification;

Fig. 11 is a perspective view of the latch utilized in the form of the invention illustrated in Fig. 10.

Referring to the drawings in detail, the con-

tainer 10, here shown as a vanity case, constructed in accordance with the present invention comprises a body portion 12, within which is a powder tray and rouge compartment frame 14 is positioned and secured, and a hinged cover comprising a main cover part 16 and an auxiliary cover part or flap 18 which is hinged to said main cover part 16. Said case is preferably made of suitable sheet metal, by stamping and bending operations. A mirror 20 is mounted in cover member 16 and is secured therein by a metal frame 22. As illustrated in Fig. 1, when the container is closed, cover member 16 covers the open side of the body portion 12 and the cover part 18 folds over and overlies the opposite side of said body portion. Said cover part 18 is releasably secured in closed position by a catch 26 which projects through an opening 27 in the body of the case for releasable engagement with a latch 28 formed on a movable latch member 30. As here shown the case 10 simulates the appearance of an envelope, the cover member 18 having the shape of a closure flap and the outer surface of the body 12 having groove 32 which outlines the side and bottom flaps of an envelope.

The part of the body 12 which underlies the cover flap 18 in the closed position of the latter is pressed inwardly to form a recess 34 conforming substantially in size and shape to said flap so that when the latter is closed the outer surface thereof lies substantially flush with the outer surface of the body 12.

The frame 14, which is made of a sheet metal stamping, comprises a powder tray 36 and a rouge compartment 38. A cover 40 for the powder tray 36 is hinged to the top of the frame 14 by a spring hinge 42 of conventional construction which tends to move said cover to open position. Cover 40 is provided with a recess 41 for a powder puff (not shown). Said cover is held in closed position by a catch 44 which is releasably engaged by a latch 46. Said latch is formed on a spring metal strip 48 which has a folded portion 50. Said strip including its folded portion is riveted adjacent one end 52 thereof to a down turned inner wall portion 54 of the frame 14. The other end 56 of strip 48 is reflexed inwardly for sliding engagement with a side wall 58 of the powder tray over a nib 60 outwardly pressed therefrom. A part of strip 48 adjacent said reflexed end 56 is slit and formed into a spring finger 62 which bears on the inner surface of the bottom wall of the body portion 12 and serves to hold the latch 46 against the under surface of the top of frame 14 in proper position adjacent the opening 64 through which the cover 55

catch 44 projects. The folded strip portion 50 has a reflexed free end 66 which engages the strip 48 adjacent latch 46. A finger piece 68 is secured to strip 50 adjacent said reflexed end portion 66 and projects through a recess 70 formed in the front side wall of frame 14. When said frame is mounted within the body 12 said finger piece 68 projects through the opening 72 in the front side wall of body portion 12. It will be observed that the relationship of the parts is such that when the finger piece 68 is pressed inwardly through the opening 72 and recess 70, the reflexed end 66 of the strip portion 50 presses against the spring strip 48 adjacent the latch 46 thereby moving said latch out of engagement with cover catch 44 and thus permitting the spring hinge 42 to move cover 40 to open position.

The latch member 30 is positioned between the bottom of the powder tray 36 and the inner surface of the bottom of the body portion 12. Said latch member 30 is made of sheet metal and the latch 28 carried thereby is formed integral therewith by being pressed outwardly therefrom, and a small opening 74 is formed through which the catch 26 projects for engagement with latch 28. One end portion 76 of latch member 30 is bent into tubular eyelet formation around a metal pin 78 secured therein. Said end portion 76 constitutes a finger piece for moving the latch member 30 to release the latch 28 from engagement with catch 26 on cover flap 18. As clearly shown in Figs. 1 and 4, finger piece 76 lies between the hinged side edges of the body 12 and cover 16 and appears as part of the hinge between said body and cover. For this purpose the body 12 is provided at its hinge edge with a recess 80 and the cover member 16 is provided with a companion recess 82, said recesses being formed between the hinge-eyelet portions 84 and 86 on the body 12 and on the cover member 16, respectively. The body 12 also has another hinge-eyelet 88 and the cover member 16 also has another hinge-eyelet 90. When the parts are assembled, the latch member 30 is positioned as illustrated in Fig. 4 with one end of the finger piece 76 abutting the adjacent end of the hinge-eyelet 84 on the body 12. One of the hinge-eyelets 86 on the cover member 16 is received in the recess between the hinge-eyelets 84 and 88 while the other hinge-eyelet 86 on the cover member 16 is received between the other hinge-eyelet 84 on the body 12 and the adjacent end of the finger piece 76 of latch member 30. Said last mentioned hinge-eyelet 84 is, of course, received in the recess between the hinge-eyelets 86 and 90 of the cover 16. The body 12 and cover member 16 as thus assembled are held in pivotal relation by a pivot pin 92 which extends through the hinge-eyelets 90, 84, and 86 and terminates at the adjacent side edge of the finger piece 76 and by a pivot pin 94 which extends through the eyelets 88, 86, and 84 and terminates at the other side edge of said finger piece.

The latch member 30 is held in projected position by a spring 96 for engagement of latch 28 with cover catch 26. The said spring is U shaped as clearly shown in Fig. 5 and is mounted within frame 14 between the inner and outer side wall portions thereof. An outwardly offset portion 98 is formed midway between the intermediate side of said spring and projects through a recess 100 formed in the rear side wall of the frame for engagement with the upwardly offset portion 102 of latch member 30. Thus spring 96 holds the latch member 30 in projected position with the finger

piece 76 in alignment with the hinge-eyelets and with the latch 28 in position to engage the cover catch 26 but allows movement of latch member 30 to retracted position for releasing said catch.

It will be observed that the frame 14 having the latch member 48 and the spring 96 assembled therewith may be inserted as a unit within the body 12 after the latch member 30 is positioned as described above and as illustrated in Fig. 4. The front and rear side edges of frame 14 are curved inwardly and outwardly as indicated at 104 for removable snap engagement with the adjacent edges of 106 of the body 12 for securing said frame within the body of the case.

It will be understood that when the cover flap 18 is in closed position with the catch 26 thereof engaged by the latch 28, said cover flap is placed under stress by reason of the slight difference in curvature between the contacting surfaces of the body and cover flap adjacent the hinge portion 19 of the latter. On this account the cover flap 18 tends to move to open position but is restrained against such movement by the engagement of catch 26 with latch 28. However, when said catch is released the cover flap 18 automatically moves to open position which is illustrated in Fig. 2. With the cover flap 18 thus opened the cover member 16 may be moved to uncover the body of the catch for access to the powder and rouge compartments, as illustrated in Fig. 3, access to the powder compartment being obtained by actuating the push-piece 68 to release the cover 40 from the latch 46.

In the form of the invention illustrated in Figs. 10 and 11, the spring 96 is dispensed with and in lieu thereof a latch member 130 is provided with integral spring arms 132 which engage the side wall of the powder tray for normally retaining the catch 128 in releasable engagement with the cover catch 26 and with the push-piece 134 in alignment with the hinge eyelets as in the construction illustrated in Fig. 1.

Thus it is seen that the constructions herein shown and described are well adapted to accompany the objects of the present invention. It will be understood, however, that the invention may be embodied otherwise than here shown and that in the embodiments illustrated certain changes in the construction and arrangement of parts may be made. Therefore, I do not wish to be limited precisely to either of the constructions herein disclosed except as may be required by the appended claims considered with reference to the prior art.

What I claim and desire to secure by Letters Patent is:

1. A container comprising a body portion, a cover therefor hinged at one side edge thereof to one side edge of said body portion and, in closed position, overlying the open side of said body portion and having a part extending beyond the opposite edge and overlying the opposite side of said body portion, means for releasably securing said part in said overlying position thereby to hold the cover releasably in closed position, said opposite side having an aperture therethrough, a latch member in said body portion having a latch element adjacent said aperture, a catch on said part projecting through said aperture in engagement with said latch element for holding said part in said cover-closed position, and spring means in engagement with said latch member for holding said latch element in releasable engagement with said catch, and a push piece carried by said latch member and movable between said side

edges of the body portion and cover for moving the latch member to release said catch, said push piece being accessible externally of the container.

5. 2. A container comprising a body portion, a cover therefor hinged at one side edge thereof to one side edge of said body portion and, in closed position, overlying the open side of said body portion and having a part extending beyond the 10 opposite edge and overlying the opposite side of said body portion, means for releasably securing said part in said overlying position thereby to hold the cover releasably in closed position, said opposite side having an aperture therethrough, a latch member and said body portion having a latch element adjacent said aperture, a catch on 15 said part projecting through said aperture in engagement with said latch element for holding said parts in said cover closed position, and a U shaped spring in engagement with said latch member for holding said latch element in releasable engagement with said catch.

3. A container comprising a body portion, a cover therefor hinged at one side edge thereof to one side edge of said body portion and, in closed position, overlying the open side of said body portion and having a part extending beyond the opposite edge and overlying the opposite side of said body portion, means for releasably 25

securing said part in said overlying position thereby to hold the cover releasably in closed position, said opposite side having an aperture therethrough, a latch member in said body portion having a latch element adjacent said aperture, a catch on said part projecting through said aperture in engagement with said latch element for holding said parts in said cover closed position, and spring means integral with said latch member and engaging a part of the container internally thereof for holding said latch element in releasable engagement with said catch. 5 10

4. A container comprising a body portion having a compartment therein, a cover for said compartment, latch means for releasably securing said cover in closed position, means for releasing said latch means movably mounted in one side wall of said body portion, said side wall having an opening through which a part of said latch releasing means projects, a second cover hinged 20 to the opposite side wall of said body portion and having a part overlying said opening and said latch releasing means of said first cover when said second cover is in closed position whereby said second cover must be moved to open position 25 before said latch releasing means can be actuated, and means for releasably securing said second cover in closed position.

JACQUES KREISLER.
